CASING FOR VEHICLE AIR CONDITIONERS

James C. Hoiby and Robert L. Westrum, Minneapolis, Minn., assignors to D. W. Onan & Sons, Inc., Minneapolis, Minn., a corporation of Minnesota

Application April 13, 1956, Serial No. 41,054

Term of patent 14 years

(Cl. D14—6)

Fig. 3

Fig. 4

Fig. 5

Fig. 1 is a view in perspective of a casing for vehicle air conditioners as seen from the rear and one side, showing my new design;

Fig. 2 is a view in top plan;

Fig. 3 is a view in front elevation;

Fig. 4 is a view in perspective showing the front and one side; and

Fig. 5 is a view in side elevation.

The side opposite that shown in Fig. 5 is identical in appearance to the side shown.

We claim:

The ornamental design for a casing for vehicle air conditioners, as shown and described.
